MINIATURE CAMERA

David Chapman, Chicago, Ill., assignor to The
Parker Pen Company, Janesville, Wis., a cor-
poration of Wisconsin

Application May 18, 1950, Serial No. 10,013

Term of patent 14 years

(Cl. D61—1)

To all whom it may concern:

Be it known that I, David Chapman, a citizen of the United States, residing at Chicago, in the county of Cook and State of Illinois, have invented a new, original, and ornamental Design for a Miniature Camera, of which the following is a specification, reference being had to the accompanying drawing, forming part thereof.

Figure 1 is a perspective view showing the front, top and one side of a camera embodying my new design.

Figure 2 is a perspective view showing the rear, bottom and opposite side thereof.

Figure 3 is a top plan view.

Figure 4 is an elevational view of one side of the camera.

The dominant features of the design reside in the portions illustrated in full lines.

I claim:
The ornamental design for a miniature camera,
as shown and described.

DAVID CHAPMAN.
